DECORATIVE SHELF COVERING

Gertrude L. Smith, Los Angeles, Calif.

Application September 8, 1936, Serial No. 99,749

3 Claims. (Cl. 41—10)

My invention relates to coverings for shelves and the like and has for its principal object to combine a sheet or strip of thin flexible material such as paper, and a narrower strip of flexible material, preferably moisture-proof, so as to form a decorative cover for shelves and the like.

Further objects of my invention are to provide a shelf covering member of the character referred to wherein the decorative member or strip is applied to the sheet that covers the shelf along the edge that overlies the front edge of the shelf so as to present a neat and finished appearance.

A further object of my invention is to provide a relatively simple, practical and inexpensive shelf cover that may be produced and sold in elongated pieces, either rolled or folded, and which pieces may be cut on transverse lines so as to fit the shelf to which the decorative coverings are applied.

A further object of my invention is to construct the decorative element of the shelf covering from moisture-proof material such as Cellophane, thin sheet Celluloid, waxed or oiled paper, rubber or rubberized fabric in order that said decorative member may be easily and quickly cleansed by the application of a damp cloth, sponge or brush, and thus enabling the said decorative member to be maintained in condition so as to present a neat, clean and finished appearance.

With the foregoing and other objects in view my invention consists in certain novel features of construction and arrangements of parts that will be hereinafter more fully described and claimed and illustrated in the accompanying drawing in which:

Fig. 1 is a perspective view with parts in section and showing one form of the decorative shelf covering in position upon a shelf.

Figs. 2, 3, 4 and 5 are perspective views of the short sections of different forms of the decorative members of my improved shelf covering.

Fig. 6 is a perspective view of a modified form of the decorative member and showing the same applied to the depending front edge of the shelf covering member.

Figs. 7, 8 and 9 are perspective views of short sections of further modified forms of decorative members as contemplated by my invention.

Figs. 10, 11 and 12 are perspective views of short sections of tape-like members equipped with reinforcing strips in order that they may be utilized as the decorative members of my improved shelf covering.

Referring by numerals to the accompanying

drawing which illustrates the invention and various modifications thereof, 10 designates a sheet or strip of thin flexible material, such as paper, or, in some instances, oil-cloth, the length and width thereof being such as to practically cover the shelf to which the completed cover member is applied, and the front edge of this strip or sheet of thin flexible material is bent downwardly, as designated by 11, so as to lie flat against the front edge of the shelf S.

Secured to the front face of the downwardly turned front edge 11 is the decorative member of the shelf covering, and which member may be constructed in various forms, as illustrated in Figs. 2 to 12 inclusive.

The decorative member comprises a strip 12 of moisture-proof material such as Cellophane, waxed or oiled paper, thin sheet rubber, or rubberized fabric, and said strip may be gathered, tucked, pleated, ruffled or otherwise treated so as to add to its attractive appearance, and the upper and lower edges of said strip may be scalloped, pinked or hemstitched, or otherwise decorated so as to present a neat and finished appearance.

In some instances the front pieces of the upper and lower edges of the decorative member 12 may be distinctively colored with respect to each other or with respect to the intermediate portion of the front surface of the strip so as to add to the appearance of the decorative member.

The decorative strip 12 is preferably secured to the depending front edge 11 of the shelf covering member by a suitable adhesive that is not affected by moisture, and I prefer to secure said strip to the front portion of the shelf covering sheet so that the upper edge of said decorative member extends slightly above the upper surface of the sheet 10, with the lower portion of the strip extending below the lower edge of the member 11, as illustrated in Figs. 1 and 6.

Thus the front edge of the shelf to which the covering is applied and the depending front edge 11 of the sheet to which the decorative member is applied, are completely hidden from view, and thus only the decorative strip 12 is observed by a person standing in front of the shelf.

To reinforce the decorative strip 12 and to hold the gathers, pleats, folds or ruffles in the strip, a narrow strip or tape-like member 13 of moisture-proof material is secured on the front face of the decorative strip 12, preferably directly opposite that portion of member 12 that is secured to the depending member 11 of the shelf covering sheet.

This reinforcing strip 13 may be colored or decorated, as desired, and to conform to the color and decorations of the strip 12.

In Fig. 2 the decorative strip 12^a is shown as being pleated vertically and the pleats held in proper position by a narrow strip 13^a.

In Fig. 4 a plurality of strips 14 of different widths are disposed one directly in front of the other and with the lower edges of said strips scalloped, as designated by 15, and the scallops disposed in staggered relation to add to the attractive appearance. If desired, the exposed scalloped edges of the underlying strips may be distinctively colored.

15 In the modified construction illustrated in Fig. 3, a pair of strips 16 of thin flexible moisture-proof material, are arranged one directly in front of the other with the lower portions of said strips slotted vertically to form fringe 17 and the fringe 20 of the two sheets may be, if desired, distinctively shaped and colored.

In this form of decorative member a narrow tape-like reinforcing strip 18 is secured by an adhesive or otherwise to the upper portion of the 25 front one of the strips 16.

In the modified construction illustrated in Fig. 5, a single strip 19 of thin flexible moisture-proof material has its lower portion slit vertically to form fringe 20, the lower portion of which fringe 30 may be scalloped or zig-zag in shape to add to the appearance thereof, and a narrow reinforcing strip 21 is secured to the upper front face of the strip 19.

35 In the modified construction illustrated in Fig. 6, the decorative member that is applied to the depending front portion 11 of the shelf covering sheet 10 comprises a strip 22 of thin flexible moisture-proof material that may be gathered or ruffled and secured by moisture-proof adhesive to the upper and lower edges of this strip are reinforcing strips 23 of thin flexible moisture-proof material that are folded double so as to overlie both front and rear faces of the edges of strip 22.

45 Thus the strips 23 reinforce the edges of the strip 22, and which construction is particularly desirable where the decorative strip is formed of thin material such as Cellophane.

The front faces of the reinforcing strips 23 may be decorated or distinctively colored.

50 Secured to the front face of strip 22, just below the upper reinforcing strip 23, is a narrow reinforcing strip 24 of thin flexible moisture-proof material.

In the modified construction illustrated in Fig. 55 7, the upper and lower edges of a thin flexible moisture-proof strip 25 are folded over onto the front face of said strip 25, thereby forming double edges, as designated by 26, and which construction reinforces the edges of the strip.

60 The front face of the folded-over portions 26 may be decorated or colored, as desired, and their edges may be scalloped or pinked to add to the decorative appearance. In this form of decorative member a narrow reinforcing strip 27 is applied to the front face of strip 25 just below and parallel with the doubled-over upper edge 26.

In the modified construction illustrated in Fig. 8, a single strip 28 of thin flexible moisture-proof material forms the decorative member, and the upper and lower edges thereof are scalloped, as designated by 29, and portions of the front face of the strip adjacent said scalloped edges may be distinctively colored or decorated.

70 A narrow reinforcing strip 30 of thin flexible moisture-proof material is secured to the front

face of strip 28 just below and parallel with the upper edge thereof.

In the modified construction illustrated in Fig. 9, a single strip 30 of thin flexible moisture-proof material has its upper and lower edges scalloped, as designated by 31, and the front face of the strip adjacent said scalloped edges may be decorated or colored as desired. This strip 30 may be gathered or ruffled and retained in such condition by a narrow reinforcing strip 32 that is secured to the front face of strip 30 just below and parallel with the upper scalloped edge.

In the modified construction illustrated in Fig. 10, a sheet of thin flexible moisture-proof material is folded double to provide a rear wall 33 and a front wall 34, the rear wall being slightly wider than the front wall so that a portion thereof extends above the upper edge of the front wall and the exposed front face of the rear wall may be colored or decorated as desired.

20 A reinforcing strip 35 is secured to the front face of the front wall just below and parallel with the upper edge thereof.

In the modified construction illustrated in Fig. 11 a strip 36 of thin flexible moisture-proof material has its edges folded over in front, as designated by 37, thus reinforcing the edges of the strip and the exposed faces of these reinforcing edges may be distinctively colored or decorated.

A narrow reinforcing strip 38 is secured on the 30 front face of strip 36 just below and parallel with the upper folded-over edge.

In the modified construction illustrated in Fig. 12 a strip 39 of thin flexible moisture-proof material has applied to its upper and lower edges reinforcing strips 40 of thin material folded double so as to overlie the front and rear faces of said strip 39 and the exposed front faces of these reinforcing strips 40 may be distinctively marked, shaped or colored.

40 A narrow reinforcing strip 41 is applied to the front face of strip 39 just below and parallel with the upper one of the strips 40.

45 Thus it will be seen that I have provided a decorative shelf covering that is relatively simple in construction, inexpensive of manufacture and very effective in performing the functions for which it is intended.

The combined elements constitute a flexible covering for a shelf or the like, including the front face of the shelf and an attractive decorative strip that extends entirely along the front edge of the shelf, and which strip adds materially to the attractive appearance of the shelf or the article of furniture to which the cover is applied.

55 The exposed decorative strip is formed of moisture-proof material in order that it may be readily cleansed by means of a damp cloth, sponge, brush or the like, and the reinforcing strips applied to the front face and the edges of the decorative member assist materially in holding the same in proper shape and preventing the edges from becoming torn.

60 It will be understood that minor changes in the size, form and construction of the various parts of my covering for shelves may be made and substituted for those herein shown and described without departing from the spirit of my invention, the scope of which is set forth in the appended claims.

70 I claim as my invention:

1. As a new article of manufacture, a decorative strip for the depending front portion of a shelf covering member comprising a strip of thin flexible material gathered between its up- 75

per and lower edges, said gathered portion being disposed closer to the upper edge of the material than to the lower edge thereof, a reinforcing strip of thin flexible material secured to the front face of said decorative strip over the gathered portion thereof, positioned below and parallel with the upper edge of said decorative strip the width of which strip is such that the ends of the gathers in the first mentioned strip extend short distances above and below the reinforcing strip and the lower edge of which decorative strip above the reinforcing strip is distinctively shaped to produce a decorative effect.

5. As a new article of manufacture, a decorative strip for the depending front portion of a shelf covering member comprising a strip of thin flexible moisture-proof material gathered between its upper and lower edges, said gathered portion being disposed closer to the upper edge of the material than to the lower edge thereof, a reinforcing strip of thin flexible moisture-proof material secured to the front face of said decorative strip over the gathered portion thereof, positioned below and parallel with the upper edge 10 of said decorative strip the width of which strip

15

10

20

25

is such that the ends of the gathers in the first mentioned strip extend short distances above and below the reinforcing strip and the lower edge of which decorative strip above the reinforcing strip is distinctively shaped to produce a decorative effect.

3. As a new article of manufacture, a decorative strip for the depending front portion of a shelf covering member comprising a strip of thin flexible moisture-proof material gathered between its upper and lower edges, said gathered portion being disposed closer to the upper edge of the material than to the lower edge thereof, a reinforcing strip of thin flexible moisture-proof material secured to the front face of said decorative strip over the gathered portion thereof and positioned below and parallel with the upper edge of said decorative strip the width of which strip is such that the ends of the gathers in the first mentioned strip extend short distances above and below the reinforcing strip and the upper and lower edges of said decorative strip being distinctly shaped so as to produce a decorative effect.
